his Attorney.

UNITED STATES PATENT OFFICE.

EMIL BUECHLER, OF CHICAGO, ILLINOIS.

WEIGH-SCALE PLATFORM.

Application filed July 1, 1926. Serial No. 119,798.

My invention relates to a weigh scale platform, and the same has for its main object the provision of platform means whereby slices of meat and other food stuffs, now commonly cut from the mass by means of a slicing machine, will fall directly from the slicing knife upon the scale platform where they may be weighed as cut off, to avoid cutting off more than the customer may require and to avoid the necessity of transferring to the scale platform successively cut off quotas or divisions before obtaining the quantity desired.

Other objects will appear hereinafter.

The invention consists in the combinations and arrangements of parts hereinafter described and claimed.

The invention will be best understood by reference to the accompanying drawing forming a part of this specification, and in which;

Fig. 1 is an elevational view showing my improved platform as it appears when applied to the weigh scales and arranged so as to receive thereon slices of food stuffs falling from the knife of the slicing machine, parts of the slicing machine and of my improved platform being shown in section;

Fig. 2 represents a top plan view of my platform; and,

Fig. 3 represents a central longitudinal view through the same.

With more particular reference to the accompanying drawing, wherein I have illustrated by way of example the preferred form of construction and arrangement of my improved weigh scale platform, the numeral 4 represents in general an elongated plate, preferably made of sheet metal, and having an enlargement or body portion 5 adapted to be substituted for the conventional platform employed on the type of weigh scales commercially known as the "Dayton" scales and herein designated by the numeral 6. Said enlargement or body portion 5 is provided with openings 7 adapted to receive screw elements 8 which are threaded into the platform supporting posts 9 that rise from the weighing mechanism contained in the base 10 of the scales.

The elongated plate 4, thus supported and secured at its enlarged end upon the platform supporting post 9, is of a length to extend well beyond the base 10 of the scales

and also to project over the platform 11 rising from the base 12 of the slicing machine 13, so that the free end of the plate will be situated below the slicing knife 14 to receive the slices of food as they are cut off from the mass and fall from the slicing knife.

Preferably and as shown, I provide the free end of the platform with retaining means comprising an end wall 15 which connects opposing side walls 16, the end wall 15 preferably being inclined outward at an angle as shown. The top side of the elongated plate and the inner faces of the end side walls are preferably provided with a coating of enamel 17, which for the sake of appearance and reasons of cleanliness is white in color. It may be remarked that the slicing machine 13 herein illustrated represents the type of slicing machine which is commercially known as a Globe electric slicer, the slicing knife 14 being operated by power received from an electric motor 18.

By making the platform so that it will extend under the slicing knife 14, the articles of food fall directly from the slicing knife onto the platform where they are weighed; and the clerk or merchant selling the food can, by watching the scales, note precisely when he has sliced off the precise quantity desired by the customer. The use of my improved platform prevents waste and saves time; and it also constitutes a sanitary provision since it is unnecessary for the clerk or merchant either to add or remove fragments with his fingers in order to obtain the desired quantity.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. As an article of manufacture, an elongated plate including a goods containing part, an arm part and an enlarged part of a form and size for attachment to and support upon the weighing mechanism of weigh scales, substantially as described.

2. As an article of manufacture, an elongated plate including a part having an outline and area adapted for attachment to and support upon the weighing mechanism of weigh scales and an outwardly extending arm part formed at its free end for containing goods to be weighed at a distance from and clear of the weighing mechanism, substantially as described.
- 10 3. As an article of manufacture, an elongated plate; an enlargement at one end of said plate of a form to provide a platform for weigh scales; and openings in said enlargement for receiving fastening elements 15 by which to secure the enlargement upon the weighing mechanism of the scales, substantially as described.
4. As an article of manufacture, an elongated plate; an enlargement at one end of said plate of a form to provide a platform 20 for weigh scales; openings in said enlargement for receiving fastening elements by which to secure the enlargement upon the weighing mechanism of the scales; connected cross and side walls rising from the free end 25 of said plate for retaining the product thereon, substantially as described.

In testimony whereof I have signed my name to this specification.

EMIL BUECHLER.
